UNITED STATES PATENT OFFICE.

ARNOLD S. CURTIS, OF MARLBORO, MASSACHUSETTS.

PROCESS OF MAKING ARCH-SUPPORT INSOLES.

Application filed July 6, 1927. Serial No. 203,851.

This invention relates to shoes designed to give effective support to the arch of the foot, and more particularly to the manufacture of insoles adapted to the relief of such infirmities as require special support for the longitudinal arch of the foot. The novel insole and the novel shoe embodying the insole form the subject-matter of a divisional application for United States Letters Patent, Serial No. 10 259,032, filed March 5, 1928.

Insoles of the type referred to have been proposed heretofore and generally they have been successful in their purpose so long as the arch supporting element retains its shape 15 and proper position, but this has been found to be difficult because of the materials used, which may not "stand up" under the heavy strains on the shoe when worn, or because of the difficulty in lasting the upper about the 20 arch support element and drawing it into its proper relation to the last when the shoe is being built.

The object of the present invention is to provide an insole which embodies an arch-support element that is preshaped to fit the instep of the last and, in addition, will retain its shape and corrective effect on the foot of the wearer of the shoe into which it is built, under the strains of wear. According- 30 ly an important feature of the invention resides in the manner in which the insole and its arch-support element are assembled to form a unitary article as will hereinafter be set forth in detail.

To the accomplishment of the above object and such others as may hereinafter appear, as will be understood from the following description by those skilled in the art, the invention comprises the manufacturing processes hereinafter described and then particularly pointed out in the appended claims.

The process of manufacture will be described by reference to the accompanying drawing in which:

45 Figure 1 is a view, in perspective, of an insole blank having a grain side lip cut at its inside shank;

Figs. 2 and 3 are views in plan and section respectively, of the arch support brace or other element to be received in the shank slit;

Fig. 4 is a view, in perspective, of the ribbed side of a welt insole showing the arch-support brace attached;

55 Fig. 5 is a fragmentary view, in plan, showing in dotted lines the initial assembly of the

arch-support brace with the insole and in the plane thereof, and showing in full lines the final, arch-fitting position of the brace, projecting upwardly and outwardly from the 60 sock face of the insole; and

Fig. 6 is a view, in cross-section, of an unbottomed welt shoe having the novel arch-support insole as a feature.

In explaining the invention the manufacture of an insole for a welt shoe will be described but those skilled in the art of shoemaking will recognize that the invention is useful in the manufacture of any type of shoe which uses an insole in its construction.

In the embodiment of the invention illustrated in the drawings an insole blank 10 shaped to fit the outline of the last bottom is fitted with a light lip 12 (Fig. 1), on its grain side or sock face throughout the inside 70 shank. This operation may readily be performed by a Goodyear insole channeling machine fitted with a straight knife and edge gage arranged adjacent to the shank edge of the insole to produce an edge slit 14 parallel thereto. The slit 14 may be made more rapidly in such a machine by running in through the heel-seat and out at the ball-line, as illustrated, but for the purposes of this invention a slit substantially as long as the 80 longitudinal dimension of the arch-support 85 brace 16 (Fig. 2) is all that is required. Thereafter, for a welt insole, the flesh side or tread face is fitted with a sewing rib 18 in any approved manner which provides a chan- 90 nel 20 and feather 22. It will be observed, from Fig. 4, that the base of the grain side lip slit 14 is somewhat inward of the between-substance or base of the sewing-rib 18 affording ample depth for receiving the brace 95 16, preferably of a relatively heavy leather such as heeling stock.

The arch-support element 16 has somewhat the shape of a box-toe but is longer in proportion to its width and its outer or arch fitting portion 24 (Fig. 2) is larger than its inner or securing margin 26. The portion 24 must be large enough to embrace the instep of the last while the portion 26 requires only sufficient material for anchorage to the insole. As seen from Fig. 3 both longitudinal edges of the brace 16 are skived as is requisite for good shoemaking.

Referring now to Fig. 5 (dot and dash lines) it will be observed that the outcurve 110 of the inner edge 28 of the element 16 is flatter than the incurve of the edge slit 14. In

order to seat the edge 28 against the base of the slit 14, as in Figs. 4 and 6, it is necessary to flex the brace 16 longitudinally. If the element 16 is bent so that it is convexed 5 toward the sock face of the sole then, when seated in the edge slit 14, it will stand upwardly and outwardly relative to said sock face and will have a shape for fitting under the instep of the foot of the wearer of the 10 shoe. The lip 12 is purposely made light so that it will be flexible enough to lift from the feather 22 as the curved element 16 is sprung beneath it to seat at the bottom of the 15 slit 14. In Fig. 5 (full lines) the arch-fitting element 16 is shown in its final, flexed form the curved form of the brace having lifted the lip 12 slightly from the feather. In practice one end of the brace 16 having first been properly positioned in the slit 14, it is stapled 20 to the feather 22, as at 30 Fig. 5, driving the staple through from the feather and clinching it on the brace beneath the turned or raised lip 12. After having been anchored at one end the element 16 may easily be 25 shaped by pressure toward its secured end to seat completely in the slit 14, its other end is then secured to retain its flexed form and thereafter the intermediate fastenings may be applied. Obviously any suitable fastening means may be used although metallic 30 staples are preferred. To complete the arch-fitting insole the under side of the lip 12 is cemented, and is then laid down on the marginal portion 26 of the shaped and 35 upstanding element 16 in any convenient manner as by a stick.

It is within the scope of the invention to vary the shape of the brace element 16 as illustrated by Fig. 2. A curved inner edge on 40 the portion 26 is preferable because, after flexing, it provides an ample margin within the slit 14 for secure anchorage but any shape that provides an adequate anchoring margin after flexure may be selected. A curved outer edge on the portion 28 is preferable because this shape better fits the upper limits 45 of the contour of the instep of the foot, permitting perfect lasting and preventing wrinkling the upper materials.

The insole is now ready for assembly on 50 the last with the counter and upper materials. It will be observed that the insole blank 10 and arch-fitting support 16 are firmly secured together and the two elements may be handled as a unitary article in the further shoemaking processes. When the insole is placed on 55 the last bottom the preshaped brace 16 fits against the contour of the instep of the last and no substantial shaping thereof is required during the lasting operation. As a result superior shoemaking is attained. Attention is particularly called to the novel process of assembling the brace and insole blank because the highly important advantage of having the brace retain its arch-fit-

ting form after being built into the shoe is obtained by securing the brace in position after, not before, it has been flexed to fit the arch.

After the upper materials have been lasted 70 the feather 22, at the inside shank, is brought into contact with the under side of the brace (Fig. 6), the slightly lifted lip 12, however, aids in causing the insole to fit the last bottom at the shank and permits easier and more 75 perfect lasting at this difficult part of the shoe. The shoe is thereafter bottomed as usual, a welt 32 being first inseamed to the sewing-rib 18 in making a welt shoe as illustrated in Fig. 6. It will be observed that in 80 a welt insole the brace 16 is secured (see Fig. 6) above the plane of the inseam and between-substance leaving the feather wholly unobstructed and hence not interfering in any way with the process of lasting as at present performed. No regard whatever need be paid by the laster to the arch-fitting brace because it assumes its proper position in the 85 shoe on assembly of the insole with the last, being a unitary part of the insole, and lies during the lasting operation entirely below the tread face of the insole and the marginal portion of the upper materials that are being manipulated.

The novel arch-support insole and the shoe 95 having said insole incorporated therein are not claimed herein because that aspect of the invention is claimed in a divisional application Serial No. 259,032, filed March 5, 1928.

The nature and scope of the invention having 100 been indicated and the preferred construction of the insole and the process of its manufacture having been specifically described, what is claimed as new, is:

1. The process of making arch-support in- 105 soles which comprises slitting the edge of an insole blank along its inside shank, preparing a brace element having a convex outer margin, and securing said brace by its inner margin between the two lips produced by 110 said edge slitting operation.

2. The process of making arch-support in- 115 soles which comprises slitting the edge of an insole blank along its inside shank, the base of said slit being substantially parallel to the 120 concave edge of the blank, preparing a brace element having an inner margin with a convexly curved edge that is flatter than the curve of the base of said slit, and finally securing said brace within said slit with its 125 inner edge seated against the base of said slit.

3. The process of making arch-support in- 130 soles which comprises slitting the edge of an insole blank along its inside shank, the base 135 of said slit being substantially parallel to the concave edge of the blank, preparing a brace element having an edge shape at its inner margin that is flatter than the curve of the base of said slit, flexing said brace element 140

longitudinally to cause its inner edge to assume a curvature substantially complementary to that of the base of said slit, and then securing said flexed brace element within said slit.

4. The process of making arch-support insoles which comprises preparing an insole blank to fit the outline of the last bottom, preparing an arch-support element having an inner edge that is convexly curved but flatter than the curve at the inside shank of said blank, and securing said element by its inner margin to the margin of said insole blank at its inner shank after first flexing said element to produce a curve at its inner edge that is substantially complementary to the curve of said inside shank.

5. The process of making arch-support insoles which comprises slitting the edge of an insole blank along its inside shank, the base of said slit being substantially parallel to the concave edge of the blank, preparing a brace element having an edge shape at its inner margin that is flatter than the curve of the base of said slit, placing said inner margin within the slit and securing one end of the element to the blank, then flexing said element by pressing toward said secured end until its inner edge is curved substantially

complementary to the curve of the base of said slit, and finally completely securing the inner margin to the insole blank while the element is held flexed.

6. The process of making arch-support insoles which comprises slitting the edge of an insole blank along its inside shank, preparing a brace element of substantial "box-toe" shape, flexing said element longitudinally, and securing said element while thus flexed within said slit.

7. The process of making arch-support insoles which comprises slitting the edge of an insole blank along its inside shank, preparing a brace element of substantial "box-toe" shape, bending said element to an arch-fitting form, and securing its flatter margin within said slit in a manner to hold said shaped element upstanding from the slit edge of the insole above its sock face.

8. The process of making arch-supporting insoles which comprises flexing a flat leather arch-support before complete attachment to the insole to substantially fit the instep portion of the last, and then completely securing the flexed arch-support to the margin of the insole at its inside shank.

ARNOLD S. CURTIS.
